ELECTRICAL CONNECTOR HOUSING HAVING A PANEL MOUNTING CONSTRUCTION

Riccardo Pautrie, Turin, Italy, assignor to
AMP Incorporated, Harrisburg, Pa.

Filed Nov. 29, 1967, Ser. No. 9,705

Claims priority, application Italy June 15, 1967

Term of patent 14 years

Int. Cl. D13—03

U.S. Cl. D26—1

Fig. 1.

Fig. 6.

Fig. 7.

FIGURE 1 is a perspective view of an electrical connector housing having a panel mounting construction, showing my new design;

FIGURE 2 is a top plan view thereof;

FIGURE 3 is an elevation as seen from the front of FIGURE 2, the opposite side being a mirror image thereof;

FIGURE 4 is an elevation as seen from the right of FIGURE 2, the opposite side being a mirror image thereof;

FIGURE 5 is a plan view as seen from the bottom of FIGURE 1;

FIGURE 6 is a perspective view of the electrical connector housing in a separated condition; and

FIGURE 7 is a plan view as seen from the top of the lower portion of the connector housing.

I claim:

The ornamental design for an electrical connector housing having a panel mounting construction, as shown and described.
